FOLDING MACHINE FOR THE MANUFACTURE OF PAPERBOARD BOXES AND THE LIKE

Whitney D. Sherman, West Nyack, and Heinz Ahlmeyer, Orangeburg, N. Y., assignors to Continental Can Company, Inc., a corporation of New York

Application July 13, 1953, Serial No. 367,418

4 Claims. (Cl. 93—52)

This invention relates to a machine for folding a paperboard flap to break the score line between the flap and the paperboard body from which the flap extends, and more particularly to a machine for folding a series of flaps projecting from one side of a continuous paperboard band and the like.

Summary

In accordance with our invention, the machine comprises a substantially flat folding sword with a diagonal edge, a member overlying the folding sword and spaced slightly therefrom, which member extends beyond the diagonal edge of the folding sword, and means for moving a paperboard body along the sword to bring a flap which extends from such body from one side of the folding sword against the diagonal edge thereof and around to the other side of the sword to be pressed against the body between the sword and the overlying member. The driving mechanism of the machine moves the paperboard body in the general direction of the score line between the body and the flap. The folding sword has a portion arranged to overlie an area of the flap outside the score line and a widened portion whose edge extends diagonally across the score line. The member which overlies the folding sword and is spaced slightly therefrom provides a channel between such member and the folding sword, through which channel the paperboard body passes during its movement in the direction aforesaid.

What the machine does essentially is to fold a paperboard flap through substantially 180° to "break" the scoreline between the flap and the paperboard body from which it extends. In the machines commonly employed for this general purpose, it is necessary for the paperboard bodies to pass completely through the machine, i. e. longitudinally past the folding sword. The reason for this is that in such machines the flap folds around the sword in such a way that the sword lies between the body and the flap. Thus the sword is "trapped," so to speak, between the body and the flap, precluding removal of the blank until it has completely passed the folding sword in a longitudinal direction. In our machine the folding sword is never trapped between the paperboard and flap; therefore it is always possible to remove the body laterally from the folding mechanism. This makes it easier to remove a damaged or torn blank from the machine. Also, it makes it possible to fold a series of flaps projecting from one side of a continuous paperboard band. This feature is of particular value in the manufacture of certain types of boxes such as hat boxes and covers therefor of round, oval or octagonal form. In such boxes, a series of flaps project from one side of a continuous paperboard band comprising either the body or the cover flange of the box. By the use of our flap folding machine, it is feasible to glue the box body or cover flange into a continuous band before the flaps are folded over for pre-breaking at the score lines. This would not be possible if the bands could not be

2

removed laterally from the folding machine, and in this case it would be necessary to pre-break the flaps before performing the operation of gluing the box bodies or cover flanges into continuous band form. With the use of our machine which does permit this lateral removal of the continuous bands, the box bodies and cover flanges can be glued in the box makers' plants and shipped in flat-folded form to customers who may then complete the manufacture of the boxes and covers with the use of our flap folding machine and other apparatus. The boxes and covers are of non-folding types, and in such a case the objective is to perform the maximum number of manufacturing steps at the box makers' plants so as to be able to use the simplest form of machinery and less experienced operators at the customers' plants. And, as stated, the use of our machine makes it possible for the box bodies and cover flanges to be pre-glued into continuous bands before they are shipped in flat-folded form to the customers.

Moreover the folding sword of our machine can be made in the form of a simple flat plate which can be manufactured at low cost and far more easily than the usual folding means which require the use of elements having spiral surfaces, compound curvature, etc. Also, our folding machine is much more compact than conventional forms of folding apparatus which generally depend for operation upon movement of the paperboard body through a considerable distance of travel.

Other objects and advantages of our invention will appear as the description proceeds.

Description

In the drawings we have illustrated a machine to show the best mode contemplated by us of carrying out our invention as applied to the flap folding or pre-breaking operation in the manufacture of bodies and cover flanges of a hat box and the like.

Fig. 1 is a side elevational view of the machine.

Fig. 2 is a front elevational view of the upper part of the same machine, to a somewhat enlarged scale.

Fig. 3 is a top plan view of the main operating elements of the machine.

Fig. 4 is an enlarged detail view of the folding sword viewed from above, showing a starting position of the continuous band with the projecting flaps which are to be folded for pre-breaking of the score line.

Fig. 5 is a similar view showing the condition of the flaps after the band has moved in the direction of the arrow a distance equal to the distance between the center lines of two successive flaps.

Fig. 6 is a similar view showing the condition of the flaps after the band has moved an additional distance equal to the distance between the center lines of two successive flaps.

Fig. 7 is a similar view showing the condition of the flaps after the band has moved a still further distance equal to the distance between the center lines of two successive flaps.

Fig. 8 is a detail sectional view taken on the line 8—8 of Fig. 4.

Fig. 9 is a detail sectional view taken on the line 9—9 of Fig. 5.

Fig. 10 is a detail sectional view taken on the line 10—10 of Fig. 6.

Fig. 11 is a detail sectional view taken on the line 11—11 of Fig. 7.

Fig. 12 is a perspective view of a continuous paperboard band of increased width suitable, for example, for the body of a hat box, and which can be processed in the same machine subject to minor adjustments of the machine to accommodate the increased width of band.

In Fig. 3 we see a portion of a continuous paperboard band B having a series of flaps F projecting from one side thereof. A conventional score line S defines the fold line between the flaps and the body of the band near the bases of the flaps.

The machine illustrated in Figs. 1-3 folds the flaps F through substantially 180° to break the score line between the flaps and the paperboard body B from which they extend. It comprises a frame 13 on which is mounted a bracket 14 supporting the driving mechanism for moving the paperboard body in the general direction of the score line S between the body and flaps. In the specific arrangement shown, this driving mechanism comprises a drive roller 15 fixed to a shaft 16 having a bearing in bracket 14 and to which is keyed a gear 17 driven by pinion 18 fixed to drive shaft 19 of motor 20 mounted on frame 13. An idler roller 21 presses the paperboard body B against the periphery of drive roller 15 or against a rubber facing 22 on the drive roller. Idler roller 21 is rotatably mounted near one end of a slide bar 23 which is pivotally mounted at 24 on the bracket 14. A pair of idler rollers 25, 26 guide the paperboard body B as it enters the machine, idler roller 25 being pivotally mounted at 27 on the bracket 14, and idler roller 26 being mounted near one end of slide bar 28 which is pivotally mounted at 29 on the bracket 14. Idler roller 26 is provided with a flange 30 to guide the paperboard body B as it enters the machine.

Slide bars 23 and 28 are provided at their inner ends with slots 31 and 32, respectively, for engagement with a pin 33 fixed to a bracket 34, the lower end of which is pivotally attached at 35 to a cross bar 36, one end of which is pivotally attached at 37 to frame 13, the other end of which is pivotally attached at 38 to the upper end of a bar 39. The lower end of the bar 39 is pivotally attached at 40 to a lever 41 which in turn is pivotally attached at 42 to the rear of frame 13. A foot treadle 43 fixed to lever 41, when depressed, pivots the slide bars 23 and 28 to raise idler rollers 21 and 26 for insertion and removal of the paperboard body B at the beginning and conclusion of the folding operation. Foot treadle 43 is normally held in its elevated position with the idler rollers 21 and 26 pressed against drive roller 15 and idler roller 25, respectively, by the action of spring 44, the upper end of which is secured to the frame 13, and the lower end of which is secured to the lever 41.

In addition to the driving mechanism which has been described, the machine comprises a folding sword 45 shown in detail in Fig. 4, having a portion 46 arranged to overlie an area of one or more of the flaps F outside the score line S, and a widened portion 47 whose edge 48 extends diagonally across the score line S, and a member 49 (Fig. 2; also seen in dot dash outline in Fig. 3) overlying folding sword 45 and spaced slightly therefrom to provide a channel 50 (Figs. 8-11) between the member 49 and folding sword 45. The paperboard body passes through channel 50 during its movement in the direction of score line S, i. e. in the direction of arrow T (Figs. 4-7). Member 49, as will be seen from Fig. 3, extends beyond the diagonally extending edge 48 of the folding sword to overlie at least a portion of the paperboard body as the latter enters channel 50. Folding sword 45 and the overlying member 49 are suitably mounted on bracket 14 as by means of angle brackets 51.

Operation

In the operation of the machine which has been described, the drive roller 15 may be driven continuously. The operator depresses treadle 43, raising idler rollers 21 and 26, whereupon he inserts the continuous band B between the idler rollers, and the idler and drive rollers. In so doing he guides the band into channel 50 between folding sword 45 and overlying member 49. However, toward the right-hand end of the folding sword, the

band is permitted to drop down against the idler roller 25 so that some of the flaps F underlie the sword. Thus, in the portion of the band which is shown in Fig. 4, the portion 46 of the sword overlies several of the flaps. 5 However, the four flaps at the left extend into the channel 50 so that they are above portion 47 of the sword.

Now the operator lifts his foot from treadle 43, whereupon idler rollers 21 and 26 are urged into the position shown in Fig. 2. Drive roller 15, moving counterclockwise, 10 drives the paperboard body in the direction of arrow T, i. e. to the left in Figs. 2-7, inclusive. As soon as the paperboard body begins to move through the machine, the flaps F at the underside of the sword are brought against the diagonal edge 48 and around to the 15 upper side of the sword to be pressed against the body B between the sword and the overlying member 49. Thus we have provided in combination a folding sword 45 in the form of a substantially flat plate having a narrow portion 46 and a widened portion 47 whose edge 20 48 extends diagonally outward from the narrow portion, and means for moving the paperboard body B over the widened portion while pressing it against the upper surface of the folding sword and bringing the flaps F extending from the paperboard body first against the lower 25 surface of the folding sword 45 and then against its upper surface as the flap is drawn over the diagonally extending edge of the folding sword. The body is drawn into the channel 50 with the flaps folded against the body so that after all of the flaps have been folded and 30 the foot treadle is again depressed, the continuous band can be removed laterally from the channel 50 by simply pulling it forward toward the operator. This completes the operation.

Referring now to Figs. 4 to 7 inclusive, we shall describe the operation of the folding sword in somewhat more detail. In Fig. 4 it will be observed that the specific one of the flaps F which is designated in lower case f, underlies the folding sword. In Figs. 5 and 9, the paperboard body B has moved to the left a distance equal to the 35 distance between the center lines of two adjacent flaps. At this point the leading edge of flap f is drawn upwardly against the diagonally extending edge 48 of the sword which exerts a leverage, forcing flap f into the position best seen in Fig. 9. In Fig. 6, the body B as advanced to the left a further distance equal to the distance 40 between the center lines of two adjacent flaps, drawing flap f against diagonal edge 48 of the sword into the position best seen in Fig. 10. In Fig. 7, the body B has advanced another increment of distance equal to that between the center lines of two adjacent flaps, at which point flap f has been drawn between the upper surface of the sword and the lower surface of the overlying member 49 so that the flap is pressed against the body as best seen in Fig. 11.

55 In the views of the drawings thus far described, the band B is relatively narrow and is suitable for use as the flange of a cover of the box. Fig. 12 shows a wider band suitable for use as the body of a box. This band may be processed with the use of the same folding sword 45 and overlying member 49, as has been described. It is desirable, however, to replace rollers 21, 22, 25 and 26 with rollers of greater width in order properly to support and guide the wider band. In operation of the machine the outward reaction to the pressure of the flaps against the diagonally extending edge 48 of the folding sword tends to urge the outer edge of the band or other paperboard body against flange 30 of roller 26, or against the flange of such wider roller as may be substituted for roller 26 in order to accommodate bands of greater widths.

70 While we have described our invention with particular reference to its application to folding a series of flaps projecting from one side of a continuous paperboard body, it will be understood that it is applicable also to folding one or more flaps projecting from other forms of paperboard bodies or blanks regardless of whether such

bodies or blanks are formed into continuous bands. In any case, it is possible with our apparatus for the paperboard blanks or other paperboard bodies or bands to be introduced laterally through the open side of the channel between the folding sword and the overlying member, and also to be removed laterally from said channel.

The terms and expressions which we have employed are used in a descriptive and not a limiting sense, and we have no intention of excluding such equivalents of the invention described, or of portions thereof, as fall within the purview of the claims.

We claim:

1. A machine for folding a series of flaps projecting from one side of a continuous paperboard band to break the score line between the flaps and the body of the paperboard band, which comprises driving mechanism for moving the paperboard band in a direction parallel to said score line, a folding sword in the form of a substantially flat untwisted plate having a portion arranged to overlie an area of the flaps outside the score line and a widened portion whose edge extends diagonally across the score line, said first-named portion of the sword lying entirely outside the path of movement of the score line so that the continuous paperboard band can be introduced laterally with unfolded flaps extending above the widened portion of the sword and other unfolded flaps extending below said first-named portion of the sword.

2. A machine according to claim 1 in which said driving mechanism is arranged to move said band in a generally circular path, bringing unfolded flaps up from below said first-named portion of the folding sword.

5 3. A machine according to claim 1 in which said driving mechanism includes a flanged wheel for holding the paperboard band after it has been introduced laterally with unfolded flaps extending above and below the sword as described.

10 4. A machine according to claim 1 in which said driving mechanism includes a flanged wheel for holding the paperboard band after it has been introduced laterally with unfolded flaps extending above and below the sword as described, and in which said driving mechanism is arranged to move said band in a generally circular path, bringing unfolded flaps up from below said first-named portion of the folding sword.
